UNITED STATES PATENT OFFICE.

FREDERICK R. PARKER, OF LA FAYETTE, INDIANA.

TELEPHONE SYSTEM.

No. 836,204.

Specification of Letters Patent.

Patented Nov. 20, 1906.

Application filed July 27, 1903. Serial No. 167,189.

To all whom it may concern:

Be it known that I, FREDERICK R. PARKER, a citizen of the United States, residing at La Fayette, in the county of Tippecanoe and State of Indiana, have invented new and useful Improvements in Telephone Systems, of which the following is a full, clear, concise, and exact description, reference being had to the accompanying drawing, forming a part of this specification.

My invention relates to a telephone system, my object being, first, to provide such a system in which the subscriber's line-signal is also used for his disconnect-signal, and, second, to provide means for operating the said signal from a central source of electricity which supplies current for operating all of the signals of the telephone-lines of the system and at the same time to furnish the subscribers' stations with individual or local sources of current for the respective substation-transmitters.

In my present invention I have shown a telephone system wherein a telephone-line extends from a substation to a central station, where it terminates in suitable connection-terminals. A signaling device is associated with the line at the central station, so that it operates over the metallic circuit of the line when no connection is made with the line, thus giving the signal for connection, and over a grounded return or common return circuit of the line when connection is made with the line, thus giving the signal for disconnection. The signaling device is associated with a central source of electricity for operating the same. The substation is provided with a local-battery circuit for supplying the substation-transmitter with talking-current. The plug-cord circuit is simply a means of connecting subscribers' lines together, there being no signaling devices nor source of electric current normally associated therewith.

45 I have illustrated my invention in the accompanying drawing, in which are shown two subscribers' lines and the central-station signaling and connecting apparatus.

The line of subscriber A extends in two limbs *j* and *k* from a substation to the central station, where the said limbs terminate in the connection-terminals *l* and *o*, respectively, of the spring-jack I. Contact *m* of the said spring-jack normally makes contact with terminal *l* and is connected to pole *t* of battery M through conductor *q*, visual lamp *s*, and

conductor *v*. Contact *p* of the said jack is conductively connected to contact *m* and is adapted to make contact with terminal *o* of the said jack when connection is made with the line. Contact *n* of the said jack normally makes contact with terminal *o* and is connected to pole *u* of battery M through conductor *r*. Pole *u* of battery M is also connected to ground through conductor *g*. Terminals *l* and *o* are adapted to disengage contacts *m* and *n*, respectively, when connection is made with the line. I have preferably shown a visual lamp *s* for the signaling device, but desire it to be understood that any other form of signaling device may be used instead. I have also shown a battery M for the central source of current, but desire it to be understood that any other source of electricity may be used instead of the said battery. A battery is not essential, as the central source of electricity, for in this invention it does not send out any current over the telephone-line during conversation over the said line. Therefore any electric generator may be used to give the signaling-currents and will not interfere with conversation over the said line.

At the substation A the limb *k* of the line is normally connected to ground through switch-hook *f* and conductor *g*. Ringer *h* and condenser *i* are normally bridged across the limbs of the telephone-line through the switch-hook *f*. Limb *j* of the telephone-line is connected in circuit with receiver *a* and winding *e* of repeating-coil C. Battery *c*, transmitter *b*, and winding *d* of repeating-coil C are connected in series, and one pole of battery *c* is connected to switch-hook *f*. When the receiver *a* is taken from the switch-hook *f*, the ground *g* and ringer *h* are disconnected from the switch-hook *f*, and the windings *e* and *d* of repeating-coil C are connected to the said switch-hook in a manner well understood.

The apparatus and connections for line B (shown upon the right of the drawing) are the same as for line A, and like characters have been employed for indicating like parts.

In the plug-cord circuit the tip-contact *u* of connecting-plug K is connected through tip-strand *u*₂, spring *u*₁ of listening-key F, contact *j*₁, winding *t*₁ of repeating-coil H, contact *k*₁, spring *l*₁, and sleeve-strand *v*₂, to sleeve-contact *v*₁. Likewise tip-contact *x*₁ of connecting-plug L is connected through tip-strand *x*₂, spring *o*₁ of ringing-key G, contact *p*₁,

winding s_1 of repeating-coil H, contact q_1 , spring r_1 , and sleeve-strand y_2 , to sleeve-contact y_1 . Contact m_1 of listening-key F is connected, through conductor w_1 , operator's receiver a_1 , and winding e_1 of repeating-coil D, to contact h_1 . Contact h_1 of listening-key F is also connected in circuit with winding d_1 of repeating-coil D, operator's transmitter b_1 , battery c_1 , and contact f_1 . Ringing-generator E has one of its terminals connected to ground through conductor g_2 , and its other terminal connected to contact n_1 of ringing-key G. When listening-key F is depressed, springs i_1 and l_1 disengage contacts j_1 and k_1 , respectively, and engage contacts h_1 and m_1 , respectively. Contact h_1 also engages contact f_1 .

When ringing-key G is depressed, springs o_1 and r_1 disengage contacts p_1 and q_1 , respectively, and spring o_1 engages contact n_1 . I preferably employ a repeating-coil H in the plug-cord circuit, but desire it to be understood that the said repeating-coil may be replaced by the well-known equivalent condensers.

If subscriber A desires to talk with subscriber B, he lifts his telephone-receiver a from the switch-hook f in the usual manner, thereby closing the circuit of battery M through conductor v , visual lamp s , conductor q , contact m of spring-jack I, jack-spring l , limb j of the telephone-line, receiver a , winding e of repeating-coil C, switch-hook f , limb k of the telephone-line, jack-spring o , contact n and conductor r , and causing visual lamp s to light, and thereby convey to the operator the signal for connection. By removing the receiver a from the switch-hook f the subscriber also closes the circuit through battery c , transmitter b , winding d of repeating-coil C, and switch-hook f , which supplies his transmitter b with current for talking purposes. The operator thereupon inserts the answering-plug K into the spring-jack I of line A, thereby causing jack-springs l and o to disengage contacts m and n , respectively, and spring o to engage contact p . The circuit of battery M, including visual lamp s , is now broken between contact n and jack-spring o and also between contact m and jack-spring l , and the said visual lamp is thus rendered inoperative. The operator then depresses her listening-key F, and thereby bridges her receiver a_1 and winding e_1 of repeating-coil D across the talking-strands u_2 and v_2 of the plug-cord circuit, and at the same time disconnects the winding t_1 of repeating-coil H from the said talking-strands u_2 and v_2 . By depressing the listening-key F the operator also closes the circuit through contact h_1 , contact f_1 , battery c_1 , transmitter b_1 , and winding d_1 of repeating-coil D, which supplies her transmitter with current for talking purposes. After learning that subscriber B is the subscriber called for the operator inserts

the calling-plug L into a spring-jack I of line B, and thereby causes jack-springs l and o thereof to disengage contacts m and n , respectively, and jack-spring o to engage contact p , and thus close the circuit of battery M, from ground at g_1 , through conductor v , visual lamp s , conductor q , contact p , jack-spring o , limb k of the telephone line and switch-hook f , to ground at g , which causes the visual lamp s , belonging to line B, to operate and convey a signal to the operator. The operator then depresses the ringing-key G, and thereby closes the circuit of ringing-generator E from ground at g_2 , through contact n_1 , spring o_1 , tip-strand x_2 , tip-contact x_1 , jack-spring l of line B, limb j of the telephone-line, condenser i , ringer h , and switch-hook f , to ground at g , thus sending a ringing-current through ringer h , and, thereby causing it to signal subscriber B. When the operator depresses the ringing-key G, she also restores listening-key F to its normal position. When subscriber B responds and lifts his receiver a from the switch-hook f , he breaks the circuit of battery M through visual lamp s , between the switch-hook f and ground g , and thereby extinguishes the signal of lamp s and renders same inoperative. Subscriber B by taking the receiver a from the switch-hook f closes the circuit from limb j of the telephone-line, through receiver a , winding e of repeating-coil C and switch-hook f , to limb k , and also the circuit of battery c through transmitter b , winding d of repeating-coil C and switch-hook f , which supplies the transmitter b with current for talking purposes. Subscribers A and B are now connected for conversation. The talking-currents from transmitter b of substation A are repeated through repeating-coil C to the metallic line of subscriber A, and thence are repeated through repeating-coil H to the line of subscriber B and substation B. The talking-currents from transmitter b of substation B are repeated through repeating-coil C to the metallic line of subscriber B, and thence are repeated through repeating-coil H to the line of subscriber A and substation A. During conversation over lines A and B one pole t of battery M is connected with the respective lines at the respective jack-contacts p of the said lines, but no current from battery M is allowed to flow.

When conversation is completed and subscriber A hangs his receiver a on the switch-hook f , he disconnects the said switch-hook from the windings d and e of repeating-coil C and connects it with ground g . This closes the circuit of battery M from ground at g_1 , through conductor v , visual lamp s , conductor q , contact p , jack-spring o , limb k of the telephone-line, and switch-hook f , to ground at g , thus causing the said visual lamp to operate and convey to the operator the signal for disconnection. When subscriber B

hangs his receiver *a* upon the switch-hook *f*, he conveys to the operator his signal for disconnection in a manner similar to that just described for subscriber A. When the operator receives both disconnect-signals, she withdraws the connecting-plugs *K* and *L* from their respective spring-jacks, and thereby restores both telephone-lines and all central-station circuits and apparatus to their normal condition. The visual lamps *s s* are rendered inoperative by having their respective circuits broken at the contacts *p p* of their respective spring-jacks.

While I have herein shown a visual lamp as the line and supervisory signal, it is evident that any other form of signaling device—such as a relay controlling a lamp, an annunciator having a visual signal, or any electrically-operable device—may be used in place 20 of the visual lamp.

While I have illustrated my present invention in connection with particular types of spring-jacks, connecting-plugs, keys, signaling devices, and sources of electric current, I 25 do not wish to confine this invention to such particular apparatus, but desire it to be understood that different forms of these several pieces of apparatus may be used.

While this invention is illustrated in connection with a switchboard of the single type, it is to be understood that its features may be adapted to switchboards of the transfer series, multiple, or divided board type.

Having described my invention, what I 35 claim as new, and desire to secure by Letters Patent, is—

1. The combination with a metallic telephone-line and connection-terminals connected thereto, of a signaling device connected to 40 the said line, a central source of electricity connected to the said device and also to the said line; a plug-cord circuit adapted to be conductively connected with the said line, means for closing the circuit of the said source through the said signaling device and the metallic telephone-line, when no connection is made with the line, and thereby operating the said device as a line-signal, and means for closing the circuit of the said source 45 through the said device and a limb of the telephone-line, with a suitable return, when connection is made with the line, and thereby operating the said device as a supervisory signal, substantially as described.

55 2. The combination with a telephone-line and connection-terminals connected thereto, of a signaling device connected to a limb of the said line, a central source of electricity connected with the said device and normally 60 with a limb of the said line, a plug-cord circuit adapted to be conductively connected with the said line, the said plug-cord circuit being normally disconnected from the said central source and said signaling device, a 65 subscriber's telephone connected with the

said line, a local source of electricity at the said telephone for supplying the transmitter thereof with current for talking purposes, the said central source being used for operating the said signaling device only, means whereby 70 the subscriber, upon lifting his receiver from the switch-hook, closes the circuit of the said central source through the said signaling device and the limbs of the telephone-line and thereby operates the said signaling device as 75 a line-signal, when no connection is made with the line, and means whereby the subscriber, upon hanging his receiver on the switch-hook, closes the circuit of the said central source through the said signaling device 80 and a limb of the telephone-line, with a suitable return, and thereby operates the said signaling device as a supervisory signal, when connection is made with the line, substantially as described. 85

3. The combination with a telephone-line and connection-terminals connected thereto, of a signaling device associated with the said line, a source of electricity associated with the said device and said line, a plug-cord circuit adapted to be conductively connected 90 to the connection-terminals of the line, means whereby, when the said connection is made with the line, the circuit of the said signaling device is changed from the metallic circuit of 95 the line to a grounded return-circuit of the line, substantially as described.

4. The combination with a telephone-line and connection-terminals connected thereto, of a signaling device at the central station 100 connected with the said line, a central source of electricity associated with the said device and normally with the said line, and adapted for supplying electric current for operating the said signaling device, but not for 105 supplying current for talking purposes, a plug-cord circuit adapted to be conductively connected with the said line, a subscriber's telephone, including a local battery for supplying the transmitter thereof with current 110 for talking purposes, at a substation, connected to the said line, means whereby the subscriber closes the circuit of the said central source through the said signaling device, and the metallic circuit of the line, and 115 thereby causes the said device to display a line-signal when no connection is made with the line, means whereby the plug-cord circuit renders the said signaling device inactive, when connection is made with the line and the 120 subscriber has his receiver removed from the switch-hook, means whereby the operation of connecting the plug-cord circuit with the telephone-line causes the said signaling device to be changed from a line-signaling circuit 125 to a supervisory signaling-circuit, and means whereby the subscriber closes the circuit of the said source through the said signaling device and a common return-circuit of the line, and thereby causes the said device 130

to display a supervisory signal, when connection is made with the line, substantially as described.

5. In a telephone system, the combination 5 with metallic telephone-lines extending from respective individual substations to the central station thereof, of a signaling device for each line and associated therewith, a telephone at each substation and connected to 10 the respective lines, a central source of current for operating all of the said signaling devices, an individual source of current for each telephone, means whereby the said central source is adapted to operate the said signaling devices over the respective metallic 15 circuits of the lines, as line-signals, means whereby the said central source is adapted to operate the said signaling devices over the respective common return-circuits of the 20 lines, as supervisory signals, and means whereby the said telephones are operated from their respective individual sources of current, substantially as described.

6. In a telephone system, the combination 25 with two telephone-lines extending from respective substations to the central station, of respective signaling devices associated with the said lines, a telephone for each line and connected thereto, a central source of 30 electricity adapted to operate the said signaling devices, a plug-cord circuit adapted for connecting the said lines together for conversation over same, the said plug-cord circuit being normally free from connection 35 with the said signaling devices and said central source, means whereby the said central source is adapted to operate the said devices as central-energy line-signals, over the respective metallic circuits of the lines when 40 no connection is made with the lines, means whereby the said central source is adapted to operate the said devices as central-energy supervisory signals, over the respective grounded return-circuits of the lines when 45 connection is made with the lines, and means whereby the said telephones are supplied with individual, local sources of current for talking purposes, substantially as described.

7. The combination with a telephone-line 50 and connection-terminals connected thereto, of a signaling device associated with the said line, a source of electricity associated with the said signaling device and normally with the said line, a plug-cord circuit adapted to 55 be conductively connected to the connection-terminals of the line, means whereby, when the said connection is made with the line, the circuit of the said signaling device and source of electricity is changed from the metallic 60 circuit of the line to a common return-circuit of the line, substantially as described.

8. The combination with a telephone-line 65 extending from a substation to the central station and terminating in suitable connection-terminals at the central station, of a

signaling device at the central station associated with the line, a central source of electricity associated with the said device and normally with the said line, a plug-cord circuit adapted to be connected with the said line, a telephone at the substation connected to the said line, means whereby the said signaling device is under control of the subscriber, as a line-signaling device, operating over the metallic circuit of the line, when no 70 connection is made with the line, and as a supervisory signaling device, operating over a common return-circuit of the line, when connection is made with the line, substantially as described.

9. In a telephone system, the combination 75 with two telephone-lines extending to the central station and terminating in suitable respective connection-terminals, of signaling devices associated with the respective lines, 80 the said devices each being adapted to give a line-signal and a supervisory signal, a central source of electricity associated with the said devices and said lines, a plug-cord circuit terminating in two connecting-plugs 85 and adapted to be connected with the said lines, the said plug-cord circuit being normally free from any signaling device or source of electricity and being used simply as a means of connecting the said lines together 90 for conversation over same, and means for operating the said signaling devices, as line-signals over respective metallic circuits of the lines and as supervisory signals over respective common return-circuits of the lines, substantially as described.

10. In a telephone system, the combination 95 with telephone-lines extending to the central station thereof, of a signaling device for each line and associated therewith, a 100 telephone for each line and connected thereto, a central source of current for operating all of the said signaling devices, an individual source of current for each telephone, means whereby the said central source is adapted 105 to operate the said signaling devices as central-energy line-signals, over respective metallic circuits of the lines, and also as central-energy supervisory signals, over respective common return-circuits of the lines, and 110 means whereby the said telephones are operated from their respective individual sources of current, substantially as described.

11. The combination with a telephone-line, of a signaling device and source of electricity in series with the line, and means at a central station whereby the said series circuit is changed from a metallic circuit of the line to a common return-circuit of the line.

12. The combination with a telephone-line, of a signaling device and source of electricity in series with the line, and means at a central station whereby the said series circuit is changed from a metallic circuit of the line to a grounded return-circuit of the line.

13. The combination with a telephone-line, of a signaling device in series with the line, and means at a central station for changing the said series circuit from a metallic circuit of the line to a common return-circuit of the line.

14. The combination with a telephone-line, of a signaling device in series with the said line, and means at a central station whereby the circuit of the telephone-line and signaling device is changed from a metallic circuit of the line to a grounded return-circuit of the line.

15. The combination with a metallic telephone-line, of a signaling device, a source of electricity, and means at a central station whereby the signaling device and source of electricity may be put in circuit with the metallic telephone-line, or in circuit with one limb of the telephone-line and a common return, one at a time.

16. The combination with a metallic telephone-line, of a signaling device, and means at a central station whereby the signaling device may be put in circuit with the metallic telephone-line, or in circuit with one limb of the telephone-line and a common return, one at a time.

17. The combination with a metallic telephone-line, of a signaling device and source of electricity in a series circuit with the metallic line, and means at a central station whereby the signaling device and source of electricity may be placed in a series circuit with one limb only of the metallic line.

18. The combination with a metallic telephone-line, of a conductive circuit including a signaling device, and means at a central station for connecting the conductive circuit in series with the metallic telephone-line, or in series with one limb only, of the telephone-line, with a suitable return, one circuit at a time.

19. The combination with a telephone-line extending to a switchboard, of a signaling device, a source of electricity, and a switch at the switchboard whereby the signaling device and source of electricity are placed in a series circuit with the metallic telephone-line, or in a series circuit with a limb of the telephone-line and a suitable return, one circuit at a time.

20. The combination with a metallic telephone-line extending from a substation to a central station, of a signaling device and source of electricity at the central station, a switch at the substation adapted to close the circuit between the limbs of the metallic line, and adapted to open the circuit between the limbs of the metallic line and connect one limb of the line to a common return, one at a time, and a switch at the central station, adapted to bridge the signaling device and source of electricity across the metallic line, or to connect said device and source in series

with one limb of the metallic line, one at a time, the said switches coöperating to operate the signaling device over a metallic circuit of the telephone-line, or over a common return-circuit of the telephone-line, substantially as described.

21. The combination with a metallic telephone-line extending from a substation to a switchboard, of a switch, signaling device and source of electricity associated with the line at the switchboard, a switch associated with the line at the substation, means provided at the said switches whereby the signaling device and source of electricity may be alternately connected in series with the metallic telephone-line and in series with one limb of the telephone-line, the said switches coöperating to operate the signaling device over the metallic circuit of the line, and over a common return-circuit of the line, one at a time, and each switch being arranged to operate the signaling device or render same inoperative, independent of the position of the other switch.

22. An electrical transmitting - line, an electrically-operable device associated therewith, and means at a central station adapted to connect the said device in circuit with the metallic line or with a limb of the line, as desired.

23. In combination, a metallic telephone-line, a signaling device and source of electricity associated with the line, means for establishing a circuit through the said source, the metallic line and the said device, to operate the latter, when no connection is made with the line, and means for establishing a circuit through the said source, one limb only of the line and the said device, with a suitable return, to operate the latter, when connection is made with the line.

24. A telephone-line extending from a substation to a central station, a switch at the substation, a connection-terminal, signaling device and source of electricity, associated with the line at the central station, the said switch and connection-terminal coöperating to alternately connect the said device and source in circuit with the metallic line or in circuit with one limb of the line and a suitable return, one at a time, to operate the said device, either the said switch or connection-terminal being adapted to operate the signaling device or render same inoperative, independent of the position of the other, substantially as described.

25. A telephone-line extending from a substation to a central station, a signaling device and source of electricity associated with the line at the central station when no connection is made with the line, and suitable circuit connections whereby the signaling device is caused to give a signal over a circuit including a limb of the line, at the moment connection is made with the line at the cen-

tral station while the apparatus at the substation is not in use.

26. An electrical transmitting-line extending from a substation to a central station, an electrically-operable device associated with the line at the central station, a normal ground connection for the line at the substation, a ground connection for the line at the central station, means whereby the said device may be operated over a circuit including both limbs of the line, when no connection is made with the line, and means whereby the said device may be operated over a circuit including one limb only of the line, when connection is made with the line, for purposes substantially as described.

27. In an electrical transmitting system, lines extending to a central station, a common return for the lines, an electrically-operable device associated with a line at the central station, and means at the central station whereby the said device may be connected in a series circuit with the limbs of the line or in circuit with one limb of the line and the common return.

28. In an electrical transmitting system, lines extending from substations to a central station, a common return for the lines, an electrically-operable device associated with each line at the central station, means whereby the said device may be operated over a circuit including the limbs of the line in series, when no connection is made with the line, and means whereby the said device may be operated over a circuit including a limb of the line and the common return, when connection is made with the line, for purposes substantially as described.

29. In an electrical transmitting system, lines extending to a central station, a common return for some of the lines, a substation on one of the lines, an electrically-operable device connected with the last-mentioned line at the central station, a normal connection from the line to the common return at the substation, and means whereby the said device may be operated over a circuit including the metallic line or over a circuit including one limb only of the line and the common return, to cause the display of a line-signal and a supervisory signal.

30. In an electrical transmitting system, lines extending from substations to a central station, a common return for the lines, a signaling device and source of electricity connected with one limb of one of the lines at the central station, a normal connection from the other limb of the last-mentioned line to the common return, at both the substation and central station, means whereby the said device may be operated from the substation over the metallic line to give a line-signal when no connection is made with the line, and means whereby the said device may be operated over a limb of the line to give a su-

pervisory signal when connection is made with the line.

31. A telephone-line extending from a substation to a central station, an electrically-operable device associated with the line at the central station, a telephone at the substation in which a limb of the line is connected to earth while the receiver is hung upon the switch-hook, and means at the central station whereby the said device may be operated over a circuit including the said limb and earth connection when connection is made with the line.

32. In a telephone system, lines extending to a central station, a common return for the lines, a substation on one of the lines, at which there is a normal connection from the line to the common return while the apparatus of the substation is not in use, an electrically-operable device associated with the line at the central station, and means at the central station whereby the said device may be operated over a circuit including a limb of the line and the common return when connection is made with the line while the substation is not in use.

33. An electrical transmitting-line extending from a substation to a central station, an electrically-operable device normally connected with one limb of the line at the central station, a normal common connection to the other limb of the line at both the substation and central station, and means whereby connection with the line operates the said device over a circuit including the last-mentioned limb only of the line.

34. In an electrical transmitting system, lines extending to a central station, a common return for the lines, a substation on one of the lines, an electrically-operable device connected with one limb of the last-mentioned line at the central station, a normal connection from the other limb of the last-mentioned line to the common return, at the substation, and means whereby connection with the line operates the said device over a circuit including the last-mentioned limb only of the line.

35. A metallic telephone-line extending from a substation to a central station, a signaling device at the central station, and suitable circuit connections and means at the central station whereby the said device may be connected in circuit with the metallic line or in circuit with one limb only of the line, and means at the substation for opening or closing either said circuit.

36. A metallic electrical transmitting-line extending from a substation to a central station, an electrically-operable device associated with the line, and suitable circuit arrangements and means at the central station whereby the said device may be connected in circuit with the metallic line or in circuit with one limb only of the line, and means at

the substation for completing, or closing either circuit.

37. A metallic telephone-line extending from a substation to a central station, a signaling device and source of electricity at the central station, and suitable circuit connections and means at the central station whereby the said device and source may be connected in circuit with the metallic line or in circuit with one limb only of the line, and means at the substation for opening or closing either said circuit.

38. A metallic electrical transmitting-line extending from a substation to a central station, an electrically-operable device and source of electricity associated with the line, and suitable circuit arrangements and means at the central station whereby the said device and source may be connected in circuit with the metallic line or in circuit with one limb only of the line, and means at the substation for completing, or closing either circuit.

39. The combination with a metallic telephone-line, of a signaling device in series therewith, and means at a central station whereby the signaling device may be placed in a series circuit with one limb only of the metallic line.

40. A metallic electrical transmitting-line extending from a substation to a central station, an electrically-operable device associated with the line, suitable electrical supply for the said device, and manually-operable means at both the substation and central station coöperating to operate the said device over the metallic circuit of the line or over a common return-circuit including a limb of the line.

41. A metallic electrical transmitting-line extending from a substation to a central sta-

tion, an electrically-operable device associated with the line, suitable electrical supply for the said device, a switch at both the substation and central station coöperating to operate the said device over the metallic circuit of the line or over a common return including a limb of the line, and a circuit arrangement such that each switch may operate the said device or render same inoperative independently of the position of the other switch.

42. In an electrical system, a three-limbed electrical line extending from one station to another, an electrically-operable device associated with the line, suitable electrical supply for the said device, means for operating the said device over limbs one and two of the line in series to give a signal, and means for operating the said device over limbs one and three of the line to give another signal, one of the limbs other than limb one being a common connection for other lines of the system.

43. A telephone-line extending from a substation to a central station, a signaling device and source of electricity associated with the line at the central station when no connection is made with the line, and suitable circuit connections whereby the signaling device is caused to give a signal over a circuit including a limb of the line, when connection is made with the line at the central station before an initiative call has been sent from the substation to the central station.

In witness whereof I have hereunto subscribed my name this 23d day of July, A. D. 1903.

FREDERICK R. PARKER.
